UNITED STATES PATENT OFFICE.

JOSEPH S. MANN, OF WORCESTER, MASSACHUSETTS, ASSIGNOR TO CROMPTON & KNOWLES LOOM WORKS, A CORPORATION OF MASSACHUSETTS.

SHUTTLE-GUIDE BLOCK FOR NARROW-WARE LOOMS.

Application filed February 8, 1922. Serial No. 535,098.

To all whom it may concern:

Be it known that I, JOSEPH S. MANN, a citizen of the United States, residing at Worcester, in the county of Worcester and 5 State of Massachusetts, have invented a new and useful Shuttle-Guide Block for Narrow-Ware Looms, of which the following is a specification.

This invention relates to a narrow ware 10 loom and particularly to the provision of improved shuttle guide blocks in such a loom. These guide blocks project upward from the lay beam and form supports for the shuttles which are moved rapidly back 15 and forth in arc-shaped grooves in the blocks.

The grooves in the guide blocks are usually undercut or T-shaped and frequently intersect in such relation that small weak 20 projections are left between adjacent grooves. Suitable reinforcement of these projections is desirable and becomes essential in extreme cases.

The reduction of friction and wear 25 between the shuttle and the guide block is also very important and for this purpose it has been more or less customary to provide wearing strips of vulcanized fiber along the sides or edges of the grooves. 30 While this reduces the friction it also materially increases the expense of manufacture.

It is the object of my invention to provide for both reinforcing the weak portions 35 of the guide block and for reducing the friction between the shuttle and the guide block, both without materially increasing the cost of manufacture.

With this general object in view, my invention relates to certain improvements in the constructive details of a shuttle guide block and also to a method or process of developing these improvements, all of 40 which will be hereinafter described and more particularly pointed out in the appended claims.

A preferred form of my invention is shown in the drawings, in which

Fig. 1 is a front elevation of a portion of 50 a lay having my improved guide blocks mounted thereon;

Fig. 2 is a front elevation of one of the guide blocks;

Fig. 3 is a side elevation thereof;

Fig. 4 is a transverse sectional view taken 55 along the line 4—4 in Fig. 2; and

Fig. 5 is a detail sectional view taken along the line 5—5 in Fig. 4.

Referring to the drawings, I have shown a portion of a lay beam 10 having shuttle 60 guiding blocks 11 and 12 mounted thereon. These guide blocks are provided with arc-shaped grooves 13, which grooves are undercut or T-shaped in section, to prevent displacement of the shuttles. 65

In the end guide blocks 11 only a single groove 13 is required but in the intermediate guide blocks 12 intersecting grooves 13 are provided, as clearly shown in Fig. 2. These grooves frequently intersect in 70 such relation that small projections 14 are left between adjacent grooves. These projections are greatly weakened by the undercutting of the groove and reinforcement thereof frequently becomes essential. 75

It will also be noted in Fig. 4 that the grooves 13 are of such depth that the guide block, as a whole, requires additional reinforcement cross-wise of the grain of the wood. 80

These parts may be conveniently and economically strengthened by the insertion of a strip 15 extending vertically along a recess in the back of the guide block and by small angularly disposed strips 16 inserted diagonally across the rear corners of the guide block and extending forward into the weakened projections 14. 85

Very satisfactory lubrication of my improved shuttle guide block may be secured 90 by impregnating the guide blocks to a limited depth below the surface with paraffine or other suitable material which is commonly applied by immersing the guide blocks therein.

An important feature of my invention relates to the method or process of carrying out the several operations so that a guide block may be formed which is lubricated as described and which is also provided with 100 the necessary reinforcement.

In carrying out this method, I first form the shaped and grooved guide block from a suitable piece of wood and then soak the block in paraffine for a period of about five 105 hours at a temperature of about 240° F. I thereafter form the slots or recesses to receive the reinforcing strips 15 and 16, cut-

ting these slots or recesses through the impregnated surface layer of the guide block to the untreated material within the block. I thereafter secure the strips 15 and 16 in the slots by the use of glue or other suitable adhesive.

By this method of procedure, I am able to combine the advantages of both lubrication and reinforcement in a single guide block 10 and at a minimum expense. This advantageous result depends largely upon the particular order in which the several steps are carried out, as otherwise the glue retaining the strips will be loosened by the high temperature of the boiling operation or the walls of the slots or recesses will become impregnated with paraffine so that the strips 15 cannot be made to adhere thereto.

Having thus described my invention, I do 20 not wish to be limited to the details herein disclosed otherwise than as set forth in the claims, but what I claim is:—

1. The method of forming a shuttle guide block, which comprises shaping and grooving 25 the guide block, impregnating the outer

portion of the guide block with a lubricant, thereafter cutting slots through the impregnated portion to the untreated material within, and adhesively securing a reinforcing strip therein.

2. The method of forming a shuttle guide block, which comprises shaping and grooving the guide block, soaking the guide block in paraffine until the block is impregnated therewith to a limited depth below the surface, thereafter cutting slots through the impregnated outer portion to the untreated material within, and adhesively securing reinforcing strips in said slots.

3. A shuttle guide block comprising a 40 piece of wood grooved to guide a shuttle, said guide block being impregnated with a lubricant to a limited depth below the surface and having slots extending below the impregnated portion, and reinforcing strips 45 adhesively secured in said slots.

In testimony whereof I have hereunto affixed my signature.

JOSEPH S. MANN.
